UNITED STATES PATENT OFFICE.

EMMONS W. BONFIELD, OF GRAND RAPIDS, MICHIGAN, ASSIGNOR TO AMERICAN BOX BOARD COMPANY, OF GRAND RAPIDS, MICHIGAN, A CORPORATION OF MICHIGAN.

PORTABLE CONTAINER.

Application filed August 24, 1925. Serial No. 51,899.

This invention relates to a portable receptacle or box made from a single piece of paper board or like material in a novel and distinctive manner which can be formed into 5 an enclosed container for various articles, particularly fruit or vegetables; which can be packed for shipment with no loss of space whatever in a car or other transporting vehicles; which can be opened when it 10 reaches its destination for the ready display of the fruit or vegetables contained therein, and which after opening and after display provides in itself an extremely convenient means for carrying the same in the same 15 manner that any receptacle with handles or the like may be carried.

This construction of receptacle also may be used in other ways which will appear fully in detail as understanding of the construction by means of which these ends are attained is had from the following description taken in connection with the accompanying drawings, in which,

Fig. 1 is a plan of the receptacle or box 25 blank from which the same is made.

Fig. 2 is a transverse section through the enclosed and sealed receptacle.

Fig. 3 is a longitudinal section therethrough.

Fig. 4 is a view similar to Fig. 2 of a receptacle made in identically the same manner but of smaller capacity and illustrating the manner in which the same may be divided into two compartments.

Fig. 5 is a perspective view of the receptacle inverted and in the position which it occupies when the fruit or vegetables are packed therein.

Fig. 6 is a perspective view of the receptacle arranged for ready carrying, and

Fig. 7 is a perspective of the same collapsed for saving of space in transportation.

Like reference characters refer to like 45 parts in the different figures of the drawings.

The box or receptacle is designed to be made from a single piece of flat stock such as paper, paper board or the like which is cut and blanked as shown in Fig. 1. In

50 this blank two rectangular sides 1 and 2 are provided which are bounded at their upper and lower edges by the lines 3 and 4 made in the blank by suitably scoring the same on such lines for ready and convenient folding.

At the lower edge of each of the sides 1 and 2 flaps 5 extend and at the upper edge of each of said side longer flaps 6 are provided which are longitudinally scored on the lines 7, making terminal sections 8, through each of which an opening 9 is cut, the same preferably being shaped substantially as the segment of a circle.

Between the adjacent ends of the sides 1 and 2 an end 10 for the receptacle is located, the sheet of material being scored on the lines 11 for suitable folding of the sides with respect to said end. At the opposite end of side 1 a similar end 10^a is located and the blank is similarly scored on the line 11^a for the same purpose. Flaps 12 extend 70 downwardly from each of the ends 10 and 10^a and may be turned inward, the blank being scored on the lines 13. The flaps 12 are separated from the flaps 5 by slots 14 cut in the blank as shown.

At the upper edge of each of the ends 10 and 10^a other and longer flaps 15 are located which are designed to be turned inwardly on the scored lines 16. The flaps 15 are separated from the flaps 6 by the cuts 17 as shown. It will be noted that the ends 10 and 10^a are in the form of trapezoids with their longer sides at the upper ends of said parts 10 and 10^a and that each of the flaps 15 has a length substantially equal to one-half of the length of the ends 1 and 2.

The blank thus made may be folded on the lines 11 and 11^a so that the free vertical edges of the side 2 and the end 10^a come together. When in this position they are secured together by a strip 18 which is glued or pasted to the contiguous end portions of said parts 2 and 10^a as shown in Figs. 5, 6 and 7. Each of the ends 10 and its connected flaps 12 and 15 are scored vertically in the blank on the lines 19 so that when the receptacle is completed by fastening the adjacent edges of the side 2 and the end 10^a together as described, the whole box may be collapsed as shown in Fig. 7 by folding 100 on the lines 19. This is necessary on account of the trapezoidal shape of the ends 10 and 10^a.

In using the receptacle for carrying fruit or vegetables it is formed into shape by 105 turning the connected flaps 6 and 8 toward each other so that one overlaps the other and then by turning the flaps 15 inwardly to-

ward each other over said first folded flaps 6 and 8. When thus formed the same are sealed or otherwise suitably secured together, preferably by sealing strips over the adjacent inner edges of the flaps 15 which, as each is one-half of the length of the sides 1 and 2 come closely together when thus folded toward each other. The receptacle is then inverted so as to occupy the position shown in Fig. 5 and the fruit or vegetables may be placed therein. It will be noted that the receptacle not being of rectangular form in cross section, when the same is filled as shown in Fig. 5, the width of the receptacle decreases upwardly. After the receptacle is filled the box is sealed by turning the flaps 5 and 12 inwardly toward each other and suitably securing and sealing the same. Then when the receptacle is inverted, by reason of the inward slant of the sides of the receptacle said sides serve to help support the layers of fruit or vegetables which have been placed therein. The lower layers within the receptacle are not subjected to all of the weight of the upper layers, in fact the greater portion of such weight is removed. This is a very valuable feature, particularly in the shipment of fruit as the crushing effect of the weight of the upper mass of fruit is in this way eliminated.

In shipping the sealed boxes or receptacles the same are placed side by side and alternately inverted so that no loss of space occurs. When the receptacles have reached their destination the flaps 15 are unsealed and disconnected, thereby permitting said flaps and also the under flaps 6 and 8 to be turned back to display the fruit or vegetables which, as the first layers packed are at the display end of the receptacle, serve to show the same to best advantage. When the fruit or other articles carried in the receptacle are sold, the flaps 15 are turned inwardly underneath the flaps 6 and 8. As said flaps 15 are each in length equal to one-half the length of the sides 1 and 2 it is evident that the entire contents within the receptacle is completely covered by the flaps 15, excluding all dust or undesired material. The outside flaps 6 and 8 may then be brought together, as shown in Fig. 6, the two openings 9 coming into conjunction through which the hand may be inserted for conveniently carrying the same. This construction is particularly practical and useful and especially so in the shipping, handling, display and merchandising of fruit or vegetables. The great utility and value of the invention is self evident. In Fig. 4 there is shown still another manner in which this invention may be used. In this case the sides 1 and 2 are of less depth

and instead of having the flaps 6 and 8 overlap each other, as shown in Fig. 2, the flaps 6 lie in the same plane and the flaps 8 are turned upwardly lying against and parallel to each other, thus forming a dividing partition at each side of which any desired article may be placed.

The invention has proved particularly valuable in actual practice. The claims define the same and all structures coming within the scope of said claims are to be considered as comprehended by said invention.

I claim:

1. A box of paper material comprising connected sides and ends, flaps turned inwardly from the lower edges of said sides and ends to make a bottom for the box, two flaps turned inwardly from the upper edges of each end and extending toward each other to completely cover the upper end of the box and two additional flaps foldably connected to the upper edges of the respective sides of the box, each of said additional flaps being wide enough to substantially cover the upper end of the box and each flap being scored longitudinally and adapted to be bent either inwardly into the box to form a partition therein or outwardly from the box to form a hand grip.

2. A box of paper material comprising, connected sides and ends, flaps turned inwardly from the lower edges of said sides and ends to make a bottom for the box, a flap turned inwardly from the upper edge of each side, each of said flaps being scored parallel to the side on a line midway between the two sides, the outer portions of the flaps beyond said score being adapted to be folded either inwardly or outwardly and the said outer portions of the flaps being of a length equal to the height of the box whereby when said flaps are folded inwardly they will form a partition in said box.

3. A box of paper material comprising connected sides and ends flaps turned inwardly from the lower edges of said sides and ends to make a bottom for the box, a flap turned inwardly from the upper edge of each side, each of said flaps being scored parallel to the side on a line midway between the two sides, the outer portions of the flaps beyond said score being adapted to be folded either inwardly or outwardly and the said outer portions of the flaps being of a length equal to the height of the box whereby when said flaps are folded inwardly they will form a partition in said box, said outer portions of the flaps being provided with hand hold openings.

In testimony whereof I affix my signature.
EMMONS W. BONFIELD.
